clined position as shown at A in Fig. 3 for insertion in a cylindrical container B. The curvature of each groove is so arranged that the stack will incline forwardly when pushed, at such an angle as to easily enter the open end of the container B.

In the front bevel side of the board 10 is a cylindrical recess 37 which is larger in diameter than the diameter of the curve of the groove 11 by an amount which corresponds to the thickness 10 of the tube which is to package the dimes from this groove. Similar cylindrical recesses are formed in front of the various grooves 38 in front of groove 12, 39 in front of groove 13, 40 in front of groove 14, and 41 in front of groove 15. Referring to Fig. 4, it is noted that there is a perpendicular wall 42 which is cut of the same height as the thickness of the wall of the tube to be inserted in front of groove 11. Similar walls are cut in front of the other grooves, in each case 20 the height being proportioned to the thickness of the wall of the tube to receive the coins from the particular groove. Each groove may have a metal lining 43 having a forwardly projecting tongue which extends out over the recess 37, the tongues 25 43, 44, 45, 46, 47, being sections of the cylinder of the lining of the corresponding groove and having a projecting tongue and may be cut away in the sides in the form of a spoon and preferably formed with material that has some 30 resiliency so that the end of the tongue is slightly adaptable when inserted in the end of a coin tube. Under the front edge of each tongue and counter-sunk in the recesses 37, 38, 39, 40, and 41 are cut-away depressions 48 which permit the 35 facile insertion of the front edge of a tube under the corresponding edge of the tongues 43, etc. As soon as the tube is passed to the rear of the recess, it straightens out and lies in parallel with the corresponding groove, the aperture in the tube 40 facing the groove to receive the inclined stack of coins as shown in Fig. 3. At the rear of each groove, a small counter-sink may be formed in the top of the recesses 37, 38, 39, 40, and 41 and a small spring 50 pinned thereto by pin 51 may 45 be positioned so that as the tube is pushed back against the wall 42, as shown in Fig. 4, the spring 50 resiliently presses on the outside wall of the tube to press the inner wall of the tube up against the under wall of the tongue 43. Similar resilient 50 means may be used under the other tongues. A modified tongue 52 is shown in Fig. 5.

Having shown and described a preferred embodiment of my invention and realizing that, in view of my disclosure, many changes will readily 55 occur in details of construction, in materials and in size and relationship of parts, and that the board 10 may be separated into one or a plurality of grooves, I do not limit myself except as in the appended claims.

60 I claim:

1. A device for packaging coins, comprising a block having a straight groove to receive a stack of coins, said groove being of such curvature in cross-section as to contact with the coins at points 65 below their center, the front end of the groove terminating in the side of the block, a tongue which is a continuation of the groove and mounted on and extending forward of the front edge of the groove and a support under the tongue on

which the end of a tube can rest, said support having a cylindrical curvature the radius of which is greater than that of a cylindrical tube to receive the coins, but open at the top for its full width.

2. A device for packaging coins comprising in combination a block having a groove to receive a stack of coins, said groove being of such curvature in cross-section as to contact with the coins only at points below their center, a support below the front edge of said groove, said support having a curvature concentric with the groove and having a radius greater than the radius of curvature of the outer wall of a package adapted to receive a stack of coins from said groove, said support being open at the top, a tongue which is a continuation of the groove, projecting from the front edge of said groove over the support, and a recess counter-sunk in the top of said support under and near the end of the tongue.

3. A device for packaging coins, comprising in combination a block having a groove to receive a stack of coins, said groove being of such curvature in cross-section as to contact with the coins only at points below their center, a tongue which is a continuation of the groove and mounted on the front edge of and extending forward of said groove, a support in the block in front of said groove, said support having a top wall curved concentrically with the groove and to conform with the outside wall of a package to be filled but open at the top for its full width, a recess counter-sunk in the top wall of said support under and near the end of said tongue, and a resilient member mounted on the block so it yieldably engages the edge of the package while the coins are being inserted.

4. A device for packaging coins, comprising in combination a flat block provided with a groove to receive a stack of coins, said groove being of such curvature in cross-section as to contact with the coins only at points below their center, the groove having a tongue, which is a continuation of the groove, at the front end, and a support in the block below the front end of the groove and of cylindrical curvature below said tongue for supporting the edge of a package but open at the top for its full width, said tongue being formed of resilient material.

5. A device for packaging coins comprising in combination, a block having a straight groove to receive a stack of coins, said groove being of such curvature in cross-section as to contact with the coins only at points below their centers, a thin forwardly projecting tongue, which is a continuation of the groove, on the lower front edge of the groove, and a support in the block in front of the groove and below the tongue and extending under the groove, the lower wall of the groove at the front having a radius of curvature no greater than the radius of the curvature of the inside of a tubular package to be filled, and said support extending up on each side of the groove so that the top of the support is less than half a cylinder and having a radius larger than that of the cylindrical outer wall of the package to be filled.
